UNITED STATES PATENT OFFICE.

CHARLES SCHEER, OF SILVERTON, COLORADO.

BOILER-FLUE CLEANER.

No. 815,043.

Specification of Letters Patent.

Patented March 13, 1906.

Application filed June 10, 1905. Serial No. 264,680.

To all whom it may concern:

Be it known that I, CHARLES SCHEER, a citizen of the United States of America, residing at Silverton, in the county of San Juan and State of Colorado, have invented new and useful Improvements in Boiler-Flue Cleaners, of which the following is a specification.

This invention relates to certain new and useful improvements in boiler-flue cleaners, the object of the invention being to provide a simple, convenient, and comparatively inexpensive device by which soot and other substances deposited within boiler-flues may be readily detached therefrom and withdrawn, and, further, to provide a cleaning device which is applicable to various sizes of flues.

The preferred embodiment of the invention is illustrated in the accompanying drawings, 20 in which—

Figure 1 is a side elevational view of the improved cleaner inserted within a flue, the latter appearing in section and a portion of the cleaner being broken away to expose the 25 expansion means. Fig. 2 is a cross-section taken on the line *a a* of Fig. 1. Fig. 3 is a detail side elevational view of a portion of the cleaner-stem, showing the adjustable cutting-knives; and Fig. 4 is a cross-section taken on 30 the line *b b* of Fig. 3.

Referring now more particularly to the drawings, the numeral 1 represents a tubular stem or shank having a screw-threaded rear end 2, adapted to receive a suitable handle 35 or operating device. The forward end of the stem is provided with a spiral or auger-shaped scraper-blade 3 and is formed at opposite sides with longitudinal slots 4, thus adapting the said forward end of the stem to 40 be expanded and contracted to adapt the blade 3 to be adjusted to operate upon the inner surfaces of flues of different sizes or diameters. In order to expand the stem, the forward or split end thereof is internally 45 threaded to receive a screw-threaded expansion-plug 5, having an outer rectangular operating-head 6, by which it may be conveniently adjusted through the medium of a wrench or other suitable tool to expand the 50 slotted portion of the stem and permit the same to contract by its natural contractile energy.

In rear of the spiral or auger-shaped scraping-blade 3 the stem 1 is formed with oppositely-disposed radial slots 7 to receive a 55 knife-holder comprising spaced plates 8, which may be fixed to the stem in any suitable manner or arranged to be detached and to frictionally engage the walls of the slots. Between these plates are arranged scraping 60 or cutting blades 9, having outer cutting edges 10 projecting beyond opposite sides of the stem and adapted to engage the wall of the flue to cut away or remove hardened particles left remaining by the spiral scraper. The two 65 knives or cutting-blades are formed with slots 11 to receive fastening-bolts 12, which pass through the spaced plates and are provided with nuts 13, by which the knives are adapted to be secured in such manner as to 70 permit them to be adjusted to engage the surfaces of flues of different diameters.

In operation the cleaner is inserted into the flue and given a reciprocatory and rotary motion, whereby the deposits will be removed from the wall of the flue by the action of the scraper and cleaning-knives, the screw further serving to feed the removed particles rearwardly in order that their convenient removal may be effected. Through the 75 expansibility of the forward portion of the stem and the adjustability of the cleaning-knives the spiral scraper and knives may be adjusted to operate upon flues of different diameters and to thoroughly remove the accumulated 80 deposits therefrom.

Having thus described the invention, what is claimed as new is—

1. A flue-cleaner provided with an expandable forward end, adjustable scraping-knives 90 in rear thereof, a spiral scraper carried by the expandable end, and means for expanding the said expandable end to vary the diameter of the spiral scraper.

2. A flue-scraper comprising a tubular 95 stem having a split expandable forward end and formed in rear thereof with radial slots, a spiral scraper surrounding said expandable end and split to expand therewith, means for expanding the said expandable end of the 100 stem and spiral scraper, scraper-blades mounted in said radial slots, and means for supporting and adjusting said blades.

3. A flue-cleaner provided with an expand-

sible forward end and radial slots in rear thereof, a spiral scraper carried by the expandible end, means for expanding the said expandible end to vary the diameter of the 5 spiral scraper, a holder projecting through said radial slots, and radially - adjustable scraper-blades carried by said holder.

In testimony whereof I affix my signature in presence of two witnesses.

CHARLES SCHEER.
